UNITED STATES PATENT OFFICE.

ALBERT F. ROBBINS, OF WALTHAM, MASSACHUSETTS.

MAINSPRING-WINDING DEVICE FOR WATCHES.

1,161,887.

Specification of Letters Patent. Patented Nov. 30, 1915.

Application filed October 3, 1914. Serial No. 864,740.

To all whom it may concern:

Be it known that I, ALBERT F. ROBBINS, a citizen of the United States, residing at Waltham, in the county of Middlesex and State of Massachusetts, have invented new and useful Improvements in Mainspring-Winding Devices for Watches and the like, of which the following is a specification.

This invention relates to improvements in mainspring winding devices for watches and the like, the object of the invention being to provide an inexpensive, simple and durable device adapted to wind substantially all sizes of watchsprings and to accomplish the same with the least amount of work and with few operations.

The invention consists in the combination and arrangement of parts whereby the above objects and certain other objects, which may hereinafter appear, are attained as set forth in the following specification and particularly pointed out in the claims.

Referring to the drawings, Figure 1 is a front elevation of the device embodying my invention. Fig. 2 is a section partly in elevation taken on the line 2—2 of Fig. 1. Fig. 3 is an enlarged longitudinal section of one of the spring barrels and its winding arbor, with the operation of winding the spring shown completed and said spring ejected from the barrel. Fig. 4 is an enlarged detail elevation of the spring ejecting disk. Fig. 5 is an enlarged detail view of one of the arbors. Fig. 6 is a perspective view of a mainspring of a watch.

Like numerals refer to like parts throughout the several views of the drawings.

In the drawings, 6 is a stationary support which may be of any suitable design or construction, and upon which is mounted a member 7. A stationary member 8, preferably constituting a spring barrel, is mounted on the support 6, said member 8 having a sleeve or cylindrical portion 9 extending through said member 7 and fastened therein by any suitable means, in the present instance it being forced or pressed into a hole 10 formed in said member 7.

The barrel 8 is cylindrical in form and open at one end, said barrel having a notch or opening 11 in its periphery. An arbor 12 is arranged to rotate relatively to said stationary member, said arbor having a projection, preferably a pin 13, arranged adjacent one end thereof which end projects into the barrel 8. The end 14 of a main spring 15,

of the usual and well known construction, which is provided with a small hole 16, is inserted through the notch 11 in the periphery of the barrel and hooked over the pin 13 after which said arbor is rotated by suitable means to wind said spring about the projecting end thereof. The opposite end of said spring is provided with a transverse bar 17 which, as said spring is wound about its arbor, engages the edges of the notch 11 and prevents said end from being drawn into the barrel. After said spring has been wound about said arbor the regular spring barrel 18 of a watch, as shown in Fig. 3, is slipped over the rim of the barrel 8 with the casing 19 of said barrel overlapping said rim after which the spring 15 is ejected from the stationary member into the barrel 18. To accomplish this an ejector 20 has been provided which preferably consists of a disk 21 arranged adjacent said stationary member, its normal position being preferably at the inner end of the barrel 8 against said inner end, providing a space between the outer face 22 of said disk and the outer end 23 of said barrel substantially equal in width to the width of the spring which is to be wound therein.

The disk 20 is provided with a sleeve 24 which extends longitudinally within the sleeve 9 and is permitted to reciprocate in said sleeve, while within the sleeve 24 the arbor 12 is preferably journaled to rotate. The inner end of the sleeve 24 is provided with an annular groove 25 within which an expansible ring 26 is inserted, said ring being at a distance from the end of the sleeve 9 sufficient to permit the sleeve 24 to reciprocate in said sleeve 9 the length of the barrel 8, or in other words permit the disk 20 to be moved lengthwise of said barrel until the outer face 22 of said disk is brought into alignment with the outer end 23 of the barrel 8.

By the construction just described it will be evident that said disk may be permitted to move relatively to the stationary member 8 and the arbor 12, while at the same time said arbor is permitted to rotate in said sleeve. By moving the disk 21 toward the end 23 of the barrel 8, after the barrel 18 has been placed over the end thereof, the spring, which has previously been wound upon the arbor 12, will be ejected from the barrel 8 into the barrel 18, the end of the transverse bar 17 entering a hole 27 in said

barrel thus freeing said spring from said stationary member.

In all previous devices of this nature at this juncture of the operation it becomes necessary to turn the arbor backwardly until the spring is unwound within the barrel 18 in order to permit the pin 13 to be disconnected from the end 14 of the spring. In the present device however this operation has been eliminated and the same means which ejects the spring from the stationary member into the barrel 18 is instrumental in disconnecting the end 14 of said spring from said pin 13. To accomplish this feature of the operation the arbor 12 is permitted to reciprocate a limited amount within the sleeve 24, said arbor having an annular shoulder 28 formed thereon which engages an annular shoulder 29 within the sleeve 24 which limits the movement of said arbor, or in other words, limits the projection of said arbor beyond the face of the disk 21. To limit the movement of the arbor 12 in the opposite direction said arbor is provided with an annular recess or groove 30. An expansible ring 31 substantially narrower than said groove is arranged in said groove and adapted to grip said disk within the sleeve thereof, permitting said arbor to be moved longitudinally in said sleeve toward the left (Figs. 2 and 3) until the side of said groove engages said ring.

The spring barrel 18 is provided with an axial projection or hub 32 upon the interior thereof which engages the end 33 of the arbor 12, when said barrel 18 is placed over the end of the barrel 8, and causes said arbor to recede into the sleeve of the disk 21 sufficient to disconnect the end 14 of said spring from the pin 13, as will be seen in Fig. 3, with the result that after said spring has been ejected from the barrel 8 and the transverse bar 17 disconnected from the notch in the periphery of said stationary member 8, said spring will be entirely disengaged from said stationary member and the inner casing 18 and the spring may be readily withdrawn without interference.

A variety of means may be employed for operating the arbor to wind the spring. The preferred method however is to provide a shaft 34 slidably and rotatably mounted in the support 6 to which a rotary motion may be imparted by a crank 40 secured to the outer end of said shaft, said shaft having a recess 35 adapted to receive the end 36 of the arbor 12. A pin 37 is arranged transversely of said recessed end and as said shaft is moved toward the arbor 12 said pin is adapted to enter a slot 38, said slot being the shorter of a pair of slots disposed in different axial planes extending longitudinally of said arbor. The pin 37 is adapted to move to the inner end of the slot 38 and permits the operator of the ma-

chine to hold the end 33 of said arbor and the pin 13 in the right relation to the notch 11 in the barrel or stationary member 8 during the winding of said spring. After the winding of said spring has been completed the shaft 34 is withdrawn from the end of said arbor and turned for a portion of a rotation sufficient to aline the pin 37 with the long slot 39 of said pair of slots.

It will be noted by referring to Fig. 3 that the long slot 39 is of such a length that clearance is at all times provided between the pin 37 and the inner end of said slot permitting the end 41 of the shaft 34, adjacent said pin 37, to engage the end of the sleeve 24 and reciprocate said sleeve without said pin engaging the end of the long slot 39. It is while the pin 37 is in said slot and in the relation just described and previous to the lateral movement of the sleeve 24 by the shaft 34 that the barrel 18 is placed over the barrel 8 and the boss or projection 32 engages the end of the arbor to move said arbor longitudinally in the sleeve 34, which movement, as hereinbefore stated, is permitted by the reason of the length of the slot 39.

To render the device more useful and practical the member 7, which supports the stationary member 8, is rotatably mounted upon a stud 42 secured to the stationary member 6, and distributed about the face of said member 7, and at an equal distance from the axis thereof are a plurality of stationary members or barrels similar to the barrel 8 only of different sizes, as indicated by "a", "b", "c", "d" and "e", these being adapted to accommodate springs of various sizes without necessitating the removal of the barrel and replacement by one of a different size. The axes of the spindles for said barrels "a", "b", "c", "d" and "e" are adapted to be moved into alinement with the shaft 34, which is common to all of said members, and which may be reciprocated to engage each of said arbors when the same have been moved into alinement with said shaft.

It will be evident by the construction set forth that any number of sets constituting or including the stationary barrel, arbor and ejector may be provided, according to the range of work which the operator desires to perform, without departing from the spirit and scope of the invention.

Having thus described my invention what I claim and desire by Letters Patent to secure is:

1. A mainspring winder having, in combination, a stationary member, a disk arranged adjacent to said stationary member, and movable relatively thereto, an arbor arranged to rotate and reciprocate relatively to said disk, said arbor having an annular groove formed therein, an expansible ring 130

arranged in and substantially narrower than said groove adapted to engage a portion of said disk and permit a longitudinal movement of said arbor relatively to said 5 disk, a projection on said arbor adapted to engage one end of a spring, means adapted to rotate said arbor to wind said spring, means on said stationary member adapted to hold the opposite end of said spring, 10 means adapted to move said arbor longitudinally to disconnect said projection from said spring, and means adapted to move said disk to disengage said spring from said stationary member.

15 2. A mainspring winder having, in combination, a stationary member, a disk arranged adjacent to said stationary member and movable relatively thereto, an arbor arranged to rotate and reciprocate in said 20 disk, said arbor having an annular groove formed therein, an expansible ring arranged within and substantially narrower than said groove adapted to grip said disk and permit a limited longitudinal movement of said 25 arbor therein, a projection on said arbor adapted to engage one end of said spring, means for rotating said arbor to wind said spring, means on said stationary member adapted to hold the opposite end of said 30 spring after said spring has been wound, and means adapted to move said disk to disengage said spring from said stationary member.

3. A mainspring winder having, in combination, a stationary member, a disk arranged adjacent to said stationary member and movable relatively thereto, an arbor arranged to rotate and reciprocate in said disk, a shoulder formed on said arbor, a 40 shoulder in said disk adapted to be engaged by the shoulder on said arbor to limit the movement of said arbor in one direction, said arbor having an annular groove formed therein, an expansible ring arranged in and 45 substantially narrower than said groove adapted to grip said disk and permit a limited longitudinal movement of said arbor away from said shoulder, a projection on said arbor adapted to engage one end of a 50 spring, means for rotating said arbor to wind said spring, means on said stationary member adapted to hold the opposite end of said spring after said spring has been wound, and means adapted to move said 55 disk relatively to said stationary member to disengage said spring therefrom.

4. A mainspring winder having, in combination, a spring barrel provided with a

notch in its periphery, an arbor rotatably arranged within said barrel, a pin on said arbor adapted to hook on to the end of a spring, means to rotate said arbor to wind said spring, means adapted to eject said spring from said barrel, and means to move said arbor longitudinally to detach said 65 spring from said pin.

5. A mainspring winder having, in combination, a stationary spring barrel, a disk normally arranged at one end of said barrel and having a sleeve extending through said 70 barrel adapted to reciprocate therein, an arbor mounted to rotate and reciprocate in said sleeve, one end of said arbor adapted to project into said barrel beyond the face of said disk, means adapted to limit the 75 projection of said arbor beyond the face of said disk, a projection on said arbor adapted to engage one end of a spring, said arbor having at its opposite end a pair of slots disposed in different axial planes, one of 80 said slots being longer than the other, a rotary shaft provided with a recess at one end adapted to receive the slotted end of said arbor, and a pin arranged transversely of said recessed end adapted to engage said 85 short slot to position and rotate said arbor and wind a spring thereabout, said pin, while engaging said long slot, being adapted to permit said arbor to be moved longitudinally relatively to said disk to disconnect 90 the end of said spring from said arbor.

6. The combination of a stationary spring barrel provided with a notch in its periphery adapted to hold one end of a spring, an arbor arranged to rotate and reciprocate 95 longitudinally within said barrel, a pin on said arbor adapted to engage the other end of said spring, means adapted to rotate said arbor to wind said spring thereabout, a watch spring barrel adapted to fit over said 100 stationary barrel, a projection in said watch spring barrel adapted to engage said arbor and move the same longitudinally of said barrel to disconnect said pin from said spring during the placing of said watch 105 spring barrel over said stationary barrel, and means adapted to eject said spring from said stationary barrel into said watch spring barrel.

In testimony whereof I have hereunto set 110 my hand in presence of two subscribing witnesses.

ALBERT F. ROBBINS.
